ACCESSORY DRILL FOR TYPE CASTING MACHINES

Cecil M. Downs, Ventura, Calif.

Application December 2, 1949, Serial No. 130,798

2 Claims. (Cl. 77—15)

1

This invention relates to an accessory drill for opening and clearing holes in the mouthpieces of type casting machines, the primary object of the invention being to provide an efficient, time and labor-saving device of this kind which is adapted to be mounted on the frames of different type-casting machines and driven by a moving part thereof.

Another important object of the invention is to provide a device of the character indicated above in an easily manipulable form whose use eliminates risk of burning of the operator's hands and breaking off of drills in the mouthpiece holes, such as commonly occurs in the practice of present methods and means for opening and clearing the holes in mouthpieces of type casting machines.

Other important objects and advantageous features of the invention will be apparent from the following description and the accompanying drawings, wherein, merely for purposes of illustration herein, a specific embodiment of the invention is set forth in detail.

In the drawings:

Figure 1 is a general schematic view showing the said embodiment installed on a line casting machine;

Figure 2 is an enlarged transverse vertical section taken through Figure 1 on the line 2—2;

Figure 3 is a top plan view of Figure 2;

Figure 4 is a vertical longitudinal section taken through the clutch and a portion of the drive cable and shield.

Referring in detail to the drawings, wherein like numerals designate like parts throughout the several views, the numeral 5 generally designates a type casting machine having a horizontally extending frame member 6 including a projecting flange 7, and having below this the main drive belt 8.

The numeral 9 designates the illustrated accessory drill which is mounted on the frame member flange 7 and driven from the main drive belt 8. The drill 9 comprises a tubular arm 10 closed at its upper end by a pipe cap 11 maintained in place by a cotter pin 12 and having an open lower end 13 into which is welded or otherwise suitably secured the pin 14 on the drive holder 15. The upper part of the tubular arm 10 is slidably telescoped through the split sleeve 16 of the mounting bracket 17; lugs 18, 18 on the sleeve 16 being traversed by a clamping screw or wing bolt 19.

Opposite the lugs 18 the sleeve 16 has an off-center, circular disc projection 20 which is faced

2

and engaged by a similar circular disc 21, the discs 20 and 21 being traversed centrally by a clamping screw or wing bolt 22, the projection 20 and sleeve 16 being swingable about an axis transverse of the mounting bracket 17. The disc 21 is on the outer end of a transverse elongated clamp bracket member 23 providing two vertically spaced arms 24, 24 to engage upper and lower sides of the machine frame member flange 7 in the manner illustrated in Figures 1 and 2, the upper arm having threaded therethrough a clamping screw or wing bolt 25 to clampably engage the upper side of the flange 7.

The sliding longitudinal and rotary adjustment 15 of the arm 10 provided by the split sleeve 16 and the clamping bolt 19, and the inward and outward or lateral adjustment provided by the clamping discs 20 and 21 and the clamping bolt 22, enable installation of the device on different 20 type casting machines, and serve as means for properly adjusting the device in operative relation to the main drive belt 8 of the machine 5.

The drive holder 15 comprises the journal 26 in which turns the bushing 27 having flanged 25 ends 28 and 29, respectively, holding the bushing in place and serving as thrust washers. Through the bore 30 of the bushing 27 is threaded the spindle 31 having a lock nut 32 on one end engaging the bushing flange 29. Between the bushing flange 28 and the opposite end of the spindle 31 is mounted the pulley or wheel 33, and a head 34 on the spindle clamps the pulley or wheel 33 on the spindle and against the bushing flange 28, with a washer 35 interposed between the head 34 and the pulley or wheel 33, the head 34 having a radial set screw 36 therein.

The spindle 31 has formed therethrough an axial bore 37 to snugly and slidably receive a flexible spring drive cable 38 which also traverses 40 the head 34 and is locked in place by the set screw 36. At the opposite end the spindle bore has an enlargement 39 into which is freely extended the flexible tubular hollow shield 40 enclosing the drive cable 38.

45 Mounted on the free end of the cable shield 40 is the chuck 41, comprising the cylindrical housing 42 having an internal, annular stop flange 43 at its forward end and having a removable, internal, annular thrust bushing 44 held in place in the rearward end by a set screw 45. The set screw 45 traverses the bushing 44 and engages the cable shield 40 to secure the chuck thereon. The cable 38 emerges from the forward end of the shield 40 and is inserted in an axial bore 46 in the cylindrical drive holder 47 and is locked in

place by a radial set screw traversing the holder. The drill holder 47 is journaled on the housing between the thrust bushing 44 and the flange 43 and has a forward extension 48 projecting through the opening provided by the flange 43 and formed with an axial bore 49 adapted to receive a drill point or drill bit 50 held in place by a set screw 51 traversing the extension 48.

With the bracket 17 clamped on the machine frame member flange 7 and the tubular arm 10 in a pendent position to place the pulley or drive wheel 33 against the under side of the main drive belt 8 of the machine 5, the arm 10 is vertically adjusted and laterally adjusted by the means above described to engage the pulley 33 with the belt in proper position and with adequate tension. The diameter of the pulley 33 is chosen so that when the machine motor (not shown) is turned on, the drill point 50 will be turned at the proper speed. To open and clear holes in the machine mouthpiece, the chuck 41 is grasped in the hand and the drill point 50 is applied successively to the holes with desirable freedom and ease provided by the flexible cable, the stable mounting of the device on the machine in the region of the work, and the efficient drive of the drill by the machine without recourse to outside power.

I claim:

1. In a type casting machine including an up-standing frame member and a main drive belt extending transversely of and spaced below the upper end of said frame member, an accessory drill for opening and clearing holes in the mouth-pieces of said machine comprising an upstanding arm having its upper end positioned adjacent to and spaced from the upper end of said frame member and having its lower end positioned adjacent said belt, a split sleeve mounted on said arm adjacent to and spaced from said upper end thereof for rotational movement and for sliding longitudinal movement, means extending through said sleeve adjacent the split for securing said sleeve in a select position of its rotational and sliding movements, a projection exteriorly of and on said sleeve and spaced from the split thereof, a mounting bracket arranged transversely of said projection and having one end connected to said projection, said projection and sleeve being swingable about an axis transverse of said bracket, means on the other end of said bracket for securing same to said frame member, a transversely disposed spindle rotatably mounted in

said arm and having one end projecting beyond said arm, a pulley on the projecting end of said spindle and engageable with said main drive belt, a flexible cable having one end secured to said spindle, a chuck, on the other end of said cable, and a drill bit rotatably supported in said chuck.

2. In a type casting machine including an up-standing frame member and a main drive belt extending transversely of and spaced below the upper end of said frame member, an accessory drill for opening and clearing holes in the mouth-pieces of said machine comprising an upstanding arm having its upper end positioned adjacent to and spaced from the upper end of said frame member and having its lower end positioned adjacent said belt, a split sleeve mounted on said arm adjacent to and spaced from said upper end thereof for rotational movement and for sliding longitudinal movement, means extending through said sleeve adjacent the split for securing said sleeve in select position of its rotational and sliding movements, a projection exteriorly of and on said sleeve and spaced from the split thereof, a mounting bracket arranged transversely of said projection and having one end connected to said projection, said projection and sleeve being swingable about an axis transverse of said bracket, means on the other end of said bracket for securing same to said frame member, a transversely disposed spindle rotatably mounted in said arm and having one end projecting beyond said arm, a pulley on the projecting end of said spindle and engageable with said main drive belt, a flexible cable having one end secured to said spindle, a hollow shield loosely surrounding said cable and having one end extending into said spindle, a chuck positioned on the other end of said shield and fixedly secured thereto, and a drill bit rotatably supported in said chuck.

CECIL M. DOWNS.
